CLAIM

The ornamental design for a flat brick border section, as shown.

DESCRIPTION

FIG. 1 is a perspective view of a flat brick border section showing our new design;

FIG. 2 is a top plan view thereof;

FIG. 3 is a side elevational view thereof;

FIG. 4 is a front elevational view thereof;

FIG. 5 is a rear elevational view thereof; and,

FIG. 6 is a bottom plan view thereof.

The broken line showing of a series of flat brick border sections and ground pegs in FIGS. 1 and 3 is for illustrative purposes only and forms no part of the claimed design.

FIG. 1

FIG. 2

FIG. 4

FIG. 3

FIG. 6

FIG. 5
